CLAIM

The ornamental design for an offset push button magazine release for a firearm, as shown and described.

DESCRIPTION

FIG. 1 is a top, front, left-side perspective view of a first embodiment of an offset magazine release for a firearm of my new design;

FIG. 2 is a top, front, right-side perspective view thereof;

FIG. 3 is a top, rear, left-side perspective view thereof;

FIG. 4 is a top, rear, right-side perspective view thereof;

FIG. 5 is a bottom, front, left-side perspective view thereof;

FIG. 6 is a bottom, front, right-side perspective view thereof;

FIG. 7 is a bottom, rear, left-side perspective view thereof;

FIG. 8 is a bottom, rear, right-side perspective view thereof;

FIG. 9 is a top plan view thereof;

FIG. 10 is a bottom plan view thereof;

FIG. 11 is a front elevational view thereof;

FIG. 12 is a rear elevational view thereof;

FIG. 13 is a right-side elevational view thereof;

FIG. 14 is a left-side side elevational view thereof;

FIG. 15 is a right-side, top perspective view thereof;

FIG. 16 is a front, bottom, right-side perspective view thereof shown in a use configuration with environment of a firearm;

FIG. 17 is an enlarged detailed view of area 17 circumscribed within FIG. 16;

FIG. 18 is top, front, left-side perspective view of a second embodiment of an offset push button magazine release for a firearm of my new design;

FIG. 19 is a top, front, right-side perspective view thereof;

FIG. 20 is a top, rear, left-side perspective view thereof;

FIG. 21 is a top, rear, right-side perspective view thereof;

FIG. 22 is a bottom, front, left-side perspective view thereof;

FIG. 23 is a bottom, front, right-side perspective view thereof;

FIG. 24 is a bottom, rear, left-side perspective view thereof;

FIG. 25 is a bottom, rear, right-side perspective view thereof;

FIG. 26 is a top plan view thereof;

FIG. 27 is a bottom plan view thereof;

FIG. 28 is a front elevational view thereof;

FIG. 29 is a rear elevational view thereof;

FIG. 30 is a right-side elevational view thereof;

FIG. 31 is a left-side elevational view thereof;

FIG. 32 is a right-side, top perspective view thereof;

(Continued)

FIG. 33 is a front, bottom, right-side perspective view thereof shown in a use configuration with environment of a firearm; and,

FIG. 34 is an enlarged detailed view of area 34 circumscribed within FIG. 33.

The broken lines in the drawings are for the purpose of illustrating portions of the offset push button magazine release for a firearm. The broken lines in FIGS. 16-17 and FIGS. 33-34 depict environmental structure and boundaries of the magnified views thereof and form no part of the claimed design.
